UNITED STATES PATENT OFFICE.

ARTHUR E. LEWIS AND JOHN L. WILSON, OF AKRON, OHIO, ASSIGNEES TO THE MILLER RUBBER CO., OF AKRON, OHIO.

CONVEYING AND ELEVATING MECHANISM.

Application filed June 3, 1928. Serial No. 283,767.

The said invention relates to improvements in the conveying and elevating mechanism of the type which forms the subject of an application of Arthur P. Lewis, filed 5 in the United States Patent Office on the 26th day of September, 1927, Serial No. 222,127. The invention aims to provide a construction in which the sheet or web will be clamped or held between rollers or cross 10 members while being elevated, thereby further obviating any danger of slippage.

It further aims to provide a construction in which the clamping or holding members will travel in concentric paths as they move 15 into and out of clamping position relative to the sheet or web.

A further object is to provide a construction in which the sheet or web may be fed to the elevating means under slight tension 20 and elevated with absence of tension.

With these and other objects in view the invention includes the novel features of construction and arrangement and combination of parts hereinafter described, the invention 25 being defined by the appended claims.

In order that the invention may be more readily understood reference is made to the accompanying drawings, in which:—

Figure 1 is a diagrammatic view illustrating 30 the conveyor as installed between two relatively remote stations, as for example, a calender, and a winding device on an upper factory floor.

Fig. 2 is a side elevation on a much larger 35 scale than Fig. 1, partly broken away.

Fig. 3 is a detail view, with parts conventionally shown, illustrating the coaction of the conveyor elements.

Fig. 4 is a horizontal section on line 4—4 40 of Fig. 2.

Fig. 5 is a detail view partly in section and partly broken away.

Fig. 6 is a section on line 6—6 of Fig. 5.

Fig. 7 is a detail view illustrating the 45 lower sprocket 26 and one form of cooperating guide.

Fig. 8 is a similar view of a modified form of guide.

Fig. 9 is a view at right angles thereto, 50 partly broken away.

Fig. 10 is an enlarged detail view of one of the upper sprockets 26^z and associated parts and,

Fig. 11 is a view at right angles thereto, 55 partly broken away.

In the present invention we provide a main conveyor Fig. 1, equipped with cross bars which conveyor has a horizontal run upon which the web is deposited in slack form so as to be supported in a series of 60 shallow loops as shown in Fig. 3. The chains of this run of the conveyor then pass around guide sprockets and ascend to a pair of elevated sprockets over which they pass in a horizontal run to another set of 65 sprockets from which they preferably extend vertically to form the ascending run of a second elevating conveyor similar to the first, after which they are again led horizontally for a desired distance and to a point of 70 use for the fabric as for instance in proximity to a winding device as shown conventionally at the upper left hand corner, Fig. 1, from which point the conveyor returns to the initial horizontal run.

The travel of the conveyor is clearly indicated by the arrows in said Fig. 1.

A second conveyor or conveyors has a vertical run parallel to or coincident with the elevating run or runs of the first conveyor, said second conveyor comprising chains which pass, at their lower end, around sprockets located between the lower sprockets of the elevating conveyor, and fast on the shaft carrying the same, this second 85 conveyor passing around another set of sprockets adjacent the upper set of sprockets of the main conveyor and positioned so that one run of said supplemental conveyor will be either in the same plane or a plane 90 closely adjacent and parallel thereto, while the return run is spaced therefrom. The second or supplemental conveyor carries presser bars or rolls supported from the conveyor by pivoted arms which presser 95 members clamp the web to the cross bars driving the elevating action.

Referring by reference characters to these drawings, the letter A designates the traveling web which is to be conveyed from a calender, elevated to a point, such as in proximity to the ceiling of the calender room, and then conveyed horizontally for a suitable distance, or to a suitable point, after which it may be again elevated if desired and further conveyed horizontally as disclosed in said application, and shown in Fig. 1.

The sheet or web coming from the calender or other continuous source of supply passes over idle rolls 3, Figs. 4 and 6, having 105 110

their axis disposed at an angle to the line of travel of the web and with their adjacent ends at the center of the web further advanced (in the direction of feed) than their 5 outer ends, whereby the rolls tend to spread the fabric or web and remove wrinkles.

A roll 2 is positioned so that the web is depressed slightly after leaving roll 1. After leaving the spreader rolls 3 the web 10 passes over another idle roll 4, another set of spreader or wrinkle removing rolls 5, similar to rolls 3, and thence to a set of driven feed rolls 6, 7 and 8, Figs. 2 and 3, around which it passes in a zig zag path. 15 Roll 6 is driven from roll 7 by a crossed belt 6^a passing around a pulley on the shaft of roll 6 and a similar pulley on the shaft of roll 7, while roll 7 is driven from roll 8 by a pair of intermeshing spur gears 9 and 9^a 20 fast respectively on the shafts of rolls 7 and 8. Rolls 6, 7 and 8 are all driven at the same surface speed.

This drive is effected by a sprocket 10 fast on the shaft of roll 8 which is connected by 25 sprocket chain 11 with a sprocket 12 on one end of a Reeves variable speed device 13, the opposite end of which carries a sprocket 14 connected by chain 15 with a sprocket 16 which latter is driven by sprocket 17 (fast 30 on the shaft of sprocket 16) and chain 18 from sprocket 19^a carried on the shaft 19 which actuates the main conveyor as hereinafter described.

The Reeves variable speed device is only 35 conventionally shown as it is well known to those skilled in the art and needs no specific description.

By means of hand wheel 20 located in a 40 position convenient to a workman, and controlling the Reeves device through sprocket chain 21 (and corresponding sprocket wheels) the speed of the rolls 6, 7 and 8 may be regulated so as to subject the portion of the sheet or web between said rolls and the 45 calender to the desired degree of tension.

The shaft of roll 8 also carries a sprocket 22^a which through chain 22 and sprocket 23^a drives a roll 23 over which the web passes and upon which it rests under the 50 action of gravity. Roll 23 is driven at a faster surface speed than roll 8 and tends to keep the fabric taut between the rolls, any excess tension being prevented by slippage. (See Fig. 3.)

Roll 23 is located approximately above the 55 shaft 24^a which carries a set of sprockets 24 around which the main conveyor chains 25 pass after leaving idle sprockets 19^a at the bottom of the descending run. From 60 sprockets 24 the said chains 25 pass, in a horizontal web receiving run, to and around a pair of sprockets 26 fast on shaft 26^a from which said chains pass, in an elevating run, to an upper set of sprockets 26^b, Figs. 1 and 10, 65 from whence they pass in a horizontal web

conveying run to sprockets 26^c from which they ascend vertically to form part of a second elevating conveyor which, as it is a duplicate of the first elevating conveyor, is shown in a conventional manner only and 70 needs no further description.

At the top the second elevating conveyor chains pass around sprockets 26^c into a horizontal run extending to any desired 75 point where they pass around terminal sprockets 26^d from which they return over suitable guide sprockets to the initial horizontal run, Fig. 1.

The conveyor chains 25 carry spaced bars 25^a which are non-rotatably connected to 80 the conveyor links and are preferably wrapped or covered with muslin to prevent the rubberized fabric from "blooming".

In practice the rolls 6, 7 and 8 are driven about 15% faster than the conveyor chains, 85 the result of which is that as the sheet or web drops from the roll 23 and is taken up by the cross bars 25^a of the web receiving run, it is festooned upon said bars or depends between them in a series of shallow loops as 90 indicated in Fig. 3.

As this horizontal run of the conveyor passes around sprockets 26 and ascends vertically, it is necessary to provide means for preventing the web from slipping downward off the conveyor bars. This is accomplished in the present case by providing an auxiliary conveyor, comprising a pair of sprocket chains 27 carrying swinging arms 28 supporting at their extremities rollers 29, 100 conveniently of wood. These chains are arranged so that the conveyor formed by said chains and rollers has an ascending run in juxtaposition to and in substantially the same plane with the ascending run of conveyor 25, the spacing of the chains and rollers and bars respectively being such that on the rising vertical runs the rollers 29 will overlie the bars 25^a thereby holding the fabric to each bar. 110

The chains 27 pass around sprockets 27^a fast on shaft 26^a inside the sprockets 26, and around idle sprockets 27^b adjacent the upper sprockets 26^c, said sprockets 27^b being desirably carried by a shaft journaled in vertically adjustable counterweighted bearings for maintaining the requisite tension on the conveyor chains (Fig. 1). 115

To effectively and accurately guide the rollers and bars, various parts are preferably 120 constructed or provided in detail as follows.

Bars 25^a are carried by approximately triangular plates 30 (Figs. 3 and 5) which correspond in length to the links of the chains 25, and are secured each to a pair 125 of adjacent pins thereof. Said pivot pins are extended at the opposite or outer sides and carry flanged wheels or rollers 31 which cooperate with or run between parallel tracks or rails 32—32^a which extend 130

throughout the vertical runs of the chains.

The rollers 29 are preferably made sectional and the sections capable of independent movement to ensure complete contact 5 from edge to edge of the fabric, and are journaled on rods 29^a, having their ends fixedly secured in openings in the ends of the arms 28 which arms are pivotally mounted on the rods 33, the ends of which 10 have reduced extensions 33^a forming chain pintles for chain 27. These chain pintles carry rollers 34 between the chain links which coact with a vertical track or rail member 35 to hold the chains and arms on 15 the upwardly moving run of the main conveyor.

Power may be applied to the main conveyor 25 in any suitable manner for driving the apparatus as for instance by connecting 20 shaft 19 to the calendar as indicated in Fig. 1.

The shaft 24^a is journaled in slideable bearings capable of being adjusted by screws 24^b to take up any undesired slack in the 25 main conveyor chains.

A guide 36 is provided adjacent sprockets 26 for deflecting the descending bars 29 forwardly (as shown in Fig. 7) to cause them to be positioned properly relative to bars 25^a.

Instead of the guide means disclosed in 30 Fig. 7 which acts directly on the rolls, we may provide a modified construction such as shown in Figs. 8 and 9. In this form, each shaft 33 supports an arm 43 provided with 35 a roller 43^a for coacting with a curved guide or track 44.

The arm 43 has an open slot or fork 43^b, which straddles the shaft 33, and the arms of the fork carry fingers 43^c which lie on 40 opposite sides of the arm 28, the parts being held in position by bolt 43^d which holds the fork on shaft 33. As the rollers 29 move from the position shown at the right of Fig. 8 towards the left, the action of gravity 45 would tend to cause them to drop down into contact with the underlying web occupying the position indicated by the dot and dash line 25 but this is prevented by the rollers 43^a contacting with guides 44, until the parts 50 start on their upward movement as shown on the left of Fig. 8. A supplemental guide 44^a may be provided to engage the lower side of the roller.

To prevent any danger of the loops of 55 stock approaching each other closely enough to stick together when the conveyor chains pass around the sprockets 26^a or in other words, change their path of movement from vertical to horizontal, we provide the 60 means shown in Figs. 10 and 11.

This consists in placing on the shaft of 65 sprocket 26^a a drum 45 loose thereon which is driven at a faster speed than said shaft (but in the same direction) by means of such as sprocket 46 fast on the drum 45,

chain 47 passing around said sprocket and another sprocket 48^a on a counter shaft 48, which shaft is driven through sprocket 48^b and chain 49 from sprocket 50 fast on said shaft of sprocket 26^a. 70

What is claimed as new is:

1. An elevating conveyor comprising a main endless conveyor having a horizontal work receiving run, and a vertical work elevating run, and an auxiliary conveyor having an elevating run in close juxtaposition to said first named elevating run, cooperating sheet engaging means carried by said main and auxiliary conveyors, said main and auxiliary conveyors passing, at the bottom 75 of the vertical run around guide wheels journaled to rotate about coincident axis, and guide wheels at the upper ends of said runs for deflecting the conveyors in opposite directions. 80

2. In an elevating conveyor for web material, a main conveyor comprising a pair of endless chains carrying cross bars, upper and lower sprockets around which said chains pass, an auxiliary conveyor comprising a pair of endless chains and presser members, upper and lower sprockets around which said last named chains pass, said last named lower sprockets being journaled between said first named lower sprockets on 90 axes coincident therewith and driven in unison therewith. 95

3. Apparatus according to claim 2 in which the presser members are mounted to have a limited movement vertically relative 100 to the auxiliary conveyor chains.

4. Apparatus according to claim 2 in which the presser members are mounted on swinging arms carried by the auxiliary conveyor chains. 105

5. Apparatus according to claim 2 in which the presser members are in the form of rollers rotatably supported by swinging arms carried by the auxiliary conveyor chains. 110

6. Apparatus according to claim 2 in which the presser members are in the form of sectional rollers, each section being capable of a limited vertical movement relative to the others and the auxiliary conveyor chains. 115

7. Apparatus according to claim 2 in which the main conveyor has a horizontal work receiving run prior to engaging the lower sprockets. 120

8. Apparatus according to claim 2 in which the main conveyor has a horizontal work receiving run prior to engaging the lower sprockets, and means are provided for depositing the web in slack formation on said horizontal run. 125

9. Apparatus according to claim 2 in which the main conveyor has a substantially horizontal work receiving run prior to engaging the lower sprockets, and a substan- 130

- tially horizontal work conveying run after leaving the upper sprockets.
10. In conveying apparatus for sheet material a pair of conveyor elements having contiguous runs, and having sheet engaging means arranged to be in staggered relation on the contiguous runs with the sheet engaging means of one element intersecting the path of movement of the other, whereby the sheet is held in sinuous form, one of said elements having an anterior run portion, and means for depositing a sheet or web in slack formation on said anterior run.
11. In conveying apparatus for sheet material a pair of conveyor elements having contiguous elevating runs and having sheet overlapping engaging means for holding the sheet in sinuous form during elevation, one of said elements having an anterior substantially horizontal run, and means for depositing the sheet thereon in slack formation.
12. In conveying apparatus for sheet material a pair of conveyor elements having contiguous elevating runs and having sheet overlapping engaging means for holding the sheet in sinuous form during elevation, one of said elements having an anterior substantially horizontal run, and means for depositing the sheet thereon in slack formation, and means for applying tension to said sheet prior to its delivery to said horizontal run.
13. In conveying apparatus for sheet material a pair of conveyor elements having contiguous elevating runs, and having sheet engaging means arranged to be in staggered and overlapping relation on the elevating runs, one of said sheet engaging means comprising bars and arms pivotally connecting the same to their conveyor element.
14. In conveying apparatus for sheet material a pair of conveyor elements having contiguous elevating runs, and having sheet engaging means arranged to be in staggered and overlapping relation on the elevating runs, one of said sheet engaging means comprising bars and arms pivotally connecting the same to their conveyor element, and deflector means coacting with said pivotally mounted bars.
15. In sheet conveying apparatus a pair of conveyor elements having contiguous elevating runs, one of said elements having an anterior substantially horizontal portion and having sheet engaging bars, said other element having sheet engaging bars mounted on swinging arms.
16. In sheet conveying apparatus a pair of conveyor elements having contiguous elevating runs, one of said elements having an
- anterior substantially horizontal portion and having sheet engaging bars, said other element having sheet engaging bars mounted on swinging arms, and deflector means for deflecting said swinging arms and bars into advanced position relative to the first named bars.
17. Endless web conveying means of the class described comprising a main conveyor including chain and connecting cross bars, said main conveyor having an elevating run and an upper lateral conveying run, lower and upper sprockets for said chains, an auxiliary conveyor having a run parallel with said elevating run and comprising chains and presser members, cooperating with said cross bars, upper and lower sprockets for said chains, means for feeding an endless web to said cross bars whereby it is suspended thereon with slack portions between the bars, and means at the upper end of the elevating run tending to move the web faster than the cross bars whereby sticking together of web portions is prevented at the point where the web is conveyed laterally.
18. Endless web conveying means of the class described comprising a main conveyor having an elevating run terminating in a lateral run, a said conveyor comprising chains and cross bars, lower and upper sprockets engaging said chains, an auxiliary conveyor having a run cooperating with said elevating run and comprising chains and presser members, means for feeding the web to the main conveyor so that it will be supported by the bars thereof with intervening slack portions, a drum for engaging said slack portions at the point where the main conveyor enters the lateral run, and means for driving the drum in the same direction as the main conveyor but at a faster speed.
19. In sheet conveying apparatus, a pair of conveyor elements having contiguous elevating runs, one of said elements having anterior and posterior substantially horizontal runs and having sheet engaging bars, said other element having sheet engaging bars movable to cooperate with the first named bars, means for feeding the sheet to the anterior run to deposit the same thereon in slack loop formation, and means at the inception of said posterior run successively taking up the slack portions of the sheet to prevent contact with succeeding slack portions.
- In testimony whereof, we affix our signatures.

ARTHUR P. LEWIS.
JOHN L. WILSON.
